Patented Apr. 15, 1919.

UNITED STATES PATENT OFFICE.

ALONZO HUMBERGER, OF CHICAGO, ILLINOIS.

WASHING-MACHINE.

1,301,055.

specification of Letters Patent. Patented Apr. 15, 1919.

Application filed October 8, 1917. Serial No. 195,430.

To all whom it may concern:

Be it known that I, ALONZO HUMBERGER, a citizen of the United States, and a resident of Chicago, in the county of Cook and State 5 of Illinois, have invented certain new and useful Improvements in Washing-Machines, of which the following is a specification.

My invention relates to washing machines, and more particularly to those of the centrifugal type. Its objects are to provide in 10 a single machine, which may be of simple construction, the general advantages of washing, rinsing and drying in a succession of closely following operations, and which 15 machine may also be employed for what is commonly known as dry washing, by which is meant washing with gasoline or the like. A specific object is to provide, in a centrifugal washer, simple and effective means for 20 continuously turning over and over the articles being washed whereby the various portions of the mass being cleaned are constantly being turned and rubbed upon each 25 other and substantially equally subjected to the action of the cleaning liquid. Another specific object is to clean at all stages with 30 comparatively clean liquid, and particularly to avoid leaving within the body of the mass being cleaned particles or agglomerations of grease and other dirt substances which 35 would be difficult to rinse out, thereby accomplishing thorough and effective cleaning at a minimum cost of time and materials. Another specific object is to provide, in a 40 washer of the character described, a continuous flow of the cleaning or rinsing liquid through the centrifugal receptacle, with means for heating the liquid during its travel. Still other specific and general objects and advantages will appear herein- 45 after.

In the accompanying drawings, which 45 form a part of this specification I have illustrated these improvements in a manner intended to show the several principles involved, as well as to indicate an advantageous structure for accomplishing the desired results. These improvements may be embodied in various other constructions, 50 however, within considerably wide limits.

In these drawings Figure 1 is a vertical medial section of the machine; and Fig. 2 is a sectional top view of the same as on the line 2-2 of Fig. 1 viewed in the direction 55 of the arrows.

The construction illustrated includes first an outer casing 10, the side wall of which, as will be noted from Fig. 2, begins closely adjacent to the centrifugal inner drum or receptacle 25 and gradually departs therefrom 60 in Archimedean spiral form, the overlapping portion 10^a being materially spaced from the overlapped portion 10^b. The side wall 10 and the portion 10^b thereof extend downward a short distance below the bottom wall 16 of the drum 25 and these side walls are then continued horizontally to form the bottom wall 11, which bottom wall 11 is continuous with the exception of the openings 13 at the middle or axial portions 65 thereof, and lies closely adjacent to the bottom 16 of the centrifugal receptacle 25. The space between the portions 10^a and 10^b of the outer casing is closed by the end wall 14 which also extends downward to the 70 lower wall 11, or to the line 15, Fig. 1. A gate 6 corresponding generally in height and width to the wall 14 is hinged at one side, as at 17 and is adapted to swing into the position shown in Fig. 2 and be held 75 there by a latch or bolt 18, thus forming a vertical channel 19 extending downward to the bottom wall 11. An opening 20 in the side wall 10 extends also to or substantially to the bottom wall 11, and in some uses of 80 the device the door 6 is swung outward and latched so as to close this opening 20 and open the channel space 19 laterally to the main interior of the outer casing 10.

The vertical channel 19 is continued underneath the wall 11, where it is indicated as channel 21. This extension 21 has vertical side walls 23 and 24, as shown by dotted lines in Fig. 2, and a lower wall 22, the upper wall thereof being a portion of the wall 90 11. These side walls 23 and 24 and the bottom wall 22 terminate in the catch basin 26 provided with the outlet valve 27, and further extensions of the channel side walls 23 and 24 terminate in the flame hood 28. A 100 partition 29 divides the lower channel 21 from the flame receiving portion of the hood 28. Opening into the flame portion of the hood 28, is the flue 31, which is given several turns in the channel 21 and numerous 105 turns in the channel 19, this coil 31 opening into the outer air or connected to any suitable suction apparatus to produce draft at 31^a. From Fig. 2 it will be observed that I have provided two such coils 31, the number 110

of which may be increased by continuing the overlapped portion 10^a as may be desired. Any suitable form of burner may be provided beneath the hood 28 to supply hot air and burning gases to the interior of the coils 31.

The outer casing 10 is covered by the top wall 37 having a central opening 38. A plate-like cover 39 closes the opening 38, the top 37 carrying a plurality of bolts 40, and the plate cover 39 having a plurality of bolt openings 41 large enough to permit the heads of the bolts 40 to pass through. Upon the cover plate 39 I provide a locking ring 42 having similarly large bolt holes 43, these bolt holes 43 having slots 44 for the shanks of the bolts extending into the upwardly inclined surfaces 45. This form of clamping ring is well known in the mechanic arts. According to this construction the cover 39 may be placed in covering position, as shown in Fig. 1, and the locking ring 42 then placed upon the plate 39 whereupon by moving the locking ring 42 so that the stems of the bolts 40 pass into the restricted slot openings 44 the heads of the bolts 40 will become engaged with these slanting surfaces 45 respectively, and the cover 39 thus become locked securely upon the top 37. The cover 39 carries the ball bearing device 48 for the driving shaft 49.

The receptacle or drum 25 is provided with a bottom wall 16 having openings 51 therein about the central stud or bearing member 52, which is rigidly secured to the bottom wall 16 as by rivets. The bearing member 52 rests upon a plurality of anti-friction balls 53 carried by reinforcing structure 54 rigidly secured to the bottom wall 11. The drum 25 has a continuous side wall 56 having inwardly extending rib-like projections, preferably in the form of continuous corrugations arranged in spiral form, the spirals extending from the bottom to the top, as well illustrated in Fig. 1.

The drum 25 has also a top wall 57 having a central opening 58 therein, which opening is provided with the cover 59 held rigidly in position by the bolts and wing nuts 60. The driving shaft 49 is rigidly secured to the cover plate 59 as by the flanged connection 61 riveted thereto.

Between the channel 21 and the openings 13 and 51 about the stud bearing 52 I provide a filter 64 slidably and removably mounted in suitable guides 65, the filter being of the width of channel 21, or as defined by the space between the dotted lines 23 and 24 of Fig. 2. This filter may be composed of sea sponge, artificial sponge, charcoal, burnt clay or any other suitable filtering material. It is preferably made in the form of a plate-like unitary structure insertible into and removable from the device at will, as indicated in Fig. 1.

The centrifugal sheet metal drum 25 is suitably apertured with a large number of openings 67 as illustrated whereby the water or other cleaning liquid may readily find egress therefrom by the centrifugal action of the device. Various other forms of porous material may be employed.

Owing to the fact that the centrifugal container 25 rotates somewhat more rapidly than the loose mass of clothing or the like within it, which mass is maintained by centrifugal force against the side walls 56, the effect of the spiral corrugations is to cause the outer edge portions of the mass to creep upward along the sides 56 and turn over inward when they reach the top thereof, and thus the mass being cleaned is continuously being turned over and over, the various portions being thereby rubbed and scrubbed upon other portions thereof and upon the walls of the drum, all with advantageous cleaning effect. The outer top wall or cover 37 may be readily removed by unscrewing the wing nuts 70. I provide also a cover 71 hinged at 72 for the vertical channel 19. The device as a whole is suitably supported by legs 73.

When it is desired to use the device for practical operations the clothing or the like is inserted into the drum 25 through the openings 38 and 58 at the top, the covers 39 and 59 being carried out of the way by moving them, together with the shaft 49, in a vertical direction. The device may be charged with the cleaning liquid either through the openings 38 and 58, or directly into the vertical channel 19, the lid 71 being turned back therefor. The burner adapted to supply the heat is started and the rotation of the drum 25 begun. This rotation will be in such direction that the screw-thread-like projections in the side wall thereof will tend to thread their way downward into the mass of clothing or the like, the action being to lift the peripheral portions of the mass upward, thus turning the mass as hereinabove described. The cleaning liquid will be forced through the apertures 67 into the outer casing 10, and owing to the spiral arrangement of the outer wall 10 the liquid will be forced around to the channel 19. It is to be understood that during the cleaning operation with the liquid the door 6 will have been swung out of the position shown in Fig. 2 and secured along the side wall 10 so as to close the opening 20 there. The cleaning liquid therefore passes directly to the vertical channel space 19 and owing to the suction action from below at the openings 13 and 51 as well as to the centrifugal action of the liquid in the drum, the liquid is forced through the filter 64, leaving behind the masses of emulsified grease and dirty substances freed by the action of the soapy water or other cleaning liquid. This

130

cleaning action continues for a sufficient period when the liquid and the dirt substances are drawn off through the valve 27. The channels 19 and 21 may conveniently be flushed at this time, after which clean water is inserted into the channel 19 and the rotation continued for rinsing the clothing or the like in the drum. For the rinsing action the filter 64 may be removed if desired.

10 After the rinsing is effected the liquid is again drawn off through the valve 27, and thereupon the drying operation may be begun. For this purpose the gate 6, Fig. 2, is swung into the position there illustrated, allowing air to escape through the opening 20. The lid 71 is also opened allowing a down draft of air through the channels 19 and 21. During the drying operation the rotation of the drum is continued, the filter preferably being removed, the air circulating through the clothing or the like with the same course of travel as did the liquid. It is pointed out as an important feature that the air may be heated by the coils 31 to quicken the drying operation. It is also pointed out that initially, or after the washing operation, water or other fluid may be admitted to the machine through the valve 27 by any well-known system or arrangement of pipes and valves connected to the fluid supply.

25 I have thus provided a device by which the various desired results pointed out are attained with notable expedition and effect.

30 In view of the possible variety of embodiments of the several features shown and described reference should be had to the appended claims to determine what is contemplated by me as being within the scope of the improvements herein set forth.

40 I claim:

1. In a washing machine of the character described, the combination of a foraminous drum having side and bottom walls mounted for centrifugal rotation on a substantially vertical axis, a casing around the sides and bottom of said drum, said casing having its side wall gradually diverging spirally in a direction away from the drum, and walls forming a channel for the cleaning liquid in communication with the interior of the casing at a place where the casing wall is materially farther from the drum than are other portions of the casing.
2. In a washing machine of the character described, the combination of a foraminous drum having side and bottom walls mounted for centrifugal rotation on a substantially vertical axis, a casing around the sides and bottom of said drum, said casing having its side wall gradually diverging spirally in a direction away from the drum, walls forming a channel for the cleaning liquid in communication with the interior of the casing at a place where the casing wall is materially
3. In a washing machine of the character described, the combination of a foraminous drum having side and bottom walls mounted for centrifugal rotation on a substantially vertical axis, a casing around the sides and bottom of said drum, said casing having its side walls gradually diverging spirally in a direction away from the drum, and walls forming a channel for the cleaning liquid in communication with the interior of the casing at a place where the casing wall is materially farther from the drum than are other portions of the casing, said channel opening into said casing at a lower portion thereof, the lower portion of said drum having an opening through which the cleaning liquid may enter the drum from the lower portion of the casing.
4. In a washing machine of the character described, the combination of a foraminous drum having side and bottom walls mounted for centrifugal rotation on a substantially vertical axis, a casing around the sides and bottom of said drum, the side wall of said casing being substantially close to the side of the drum at one portion thereof and gradually diverging away from the drum spirally, portions of the casing substantially overlapping each other in materially spaced apart relation, an end wall closing the space between said overlapped portions, walls forming a channel in communication with the space between said overlapped portions of the casing, said channel opening to the interior of the casing in the lower portion thereof.
5. In a washing machine of the character described, the combination of a foraminous drum mounted for centrifugal rotation on a substantially vertical axis, a casing around the sides and bottom of said drum, the side wall of said casing being substantially close to the side of the drum at one portion thereof and gradually diverging away from the drum spirally, portions of the casing substantially overlapping each other in materially spaced apart relation, a wall closing the space between said overlapped portions, walls forming a channel in communication with a space between said overlapped portions of the casing, said channel opening to the interior of the casing in the lower portion thereof, and a readily removable filter in said channel.
6. In a washing machine of the character described, the combination of a foraminous

drum mounted for centrifugal rotation on a substantially vertical axis, a casing around the sides and bottom of said drum, the side wall of said casing being substantially close to the side of the drum at one portion thereof and gradually diverging away from the drum spirally, portions of the casing substantially overlapping each other in materially spaced apart relation, a wall closing the space between said overlapped portions, and walls forming a channel in communication with the lower portion of the space between said overlapped portions of the casing, said channel opening to the interior of the casing in the lower portion thereof, said drum having an opening in the lower portion thereof for admitting cleaning liquid thereinto from the lower portion of the casing.

7. In a washing machine of the character described, the combination of a foraminous drum having side and bottom walls mounted for centrifugal rotation on a substantially vertical axis, a casing around the sides and bottom of said drum, the bottom of said casing and the bottom of said drum having an opening to admit cleaning fluid therethrough, walls forming a channel for the fluid leading from side portions of the casing to said openings, and a hopper-like collecting receptacle in said channel.

8. In a washing machine of the character described, the combination of a foraminous drum having side and bottom walls mounted for centrifugal rotation on a substantially vertical axis, a casing around the sides and bottom of said drum, the bottom of said casing and the bottom of said drum having an opening to admit cleaning fluid therethrough, walls forming a channel for the fluid leading from side portions of the casing to said openings, a hopper-like collecting receptacle in said channel, and a filter substantially above said receptacle and in the path of liquid flow from said channel to the interior of the drum.

9. In a washing machine of the character described, the combination of a foraminous drum having side and bottom walls mounted for centrifugal rotation on a substantially vertical axis, a casing around the sides and bottom of said drum, the bottom of said casing and the bottom of said drum having an opening to admit cleaning fluid therethrough, walls forming a channel for the fluid leading from side portions of the casing to said openings, a hopper-like collecting receptacle in said channel, and a filter in said channel.

10. In a washing machine of the character described, the combination of a substantially inclosed foraminous drum mounted for rotation, a substantially inclosed casing for said drum, walls forming a channel for collecting the cleaning liquid discharged from the drum, said channel opening into said casing, said

drum having an opening to admit the cleaning fluid from the casing to the interior of the drum, and a filter intermediate the interior of the drum and the portion of the casing where the liquid is collected for flow through said channel.

11. In a washing machine of the character described, the combination of a casing, a foraminous drum mounted to rotate therein, said drum having on its side wall a plurality of projections inwardly extending and arranged spirally, for the purpose described.

12. In a washing machine of the character described, the combination of a casing, a foraminous drum mounted to rotate therein, said drum having on its side wall a plurality of rib-like projections inwardly extending and arranged spirally, for the purpose described.

13. In a washing machine of the character described, the combination of a casing, a foraminous drum mounted to rotate therein, said drum having on its side wall a plurality of corrugations arranged spirally, for the purpose described.

14. In a washing machine of the character described, the combination of a foraminous drum having side and bottom walls mounted for centrifugal rotation on a substantially vertical axis, a casing around the sides and bottom of said drum, said drum having on its side walls inwardly extending projections arranged spirally, for the purpose described.

15. In a washing machine of the character described, the combination of a foraminous drum having side and bottom walls mounted for centrifugal rotation on a substantially vertical axis, a casing around the sides and bottom of said drum, said drum having its side walls corrugated with spiral projections, for the purpose described.

16. In a washing machine of the character described, the combination of a foraminous drum having side and bottom walls mounted for centrifugal rotation on a substantially vertical axis, a casing around the sides and bottom of said drum, said drum having its side walls corrugated with spiral projections, walls forming a channel leading from the interior of side portions of the casing to the interior of bottom portions thereof, the drum having an opening in the bottom portion thereof to receive liquid thereinto.

17. In a washing machine of the character described, the combination of a foraminous drum having side and bottom walls mounted for centrifugal rotation on a substantially vertical axis, a casing around the sides and bottom of said drum, said casing having its side wall gradually diverging spirally in a direction away from the drum, walls forming a channel for the cleaning liquid in communication with the interior of the casing.

at a place where the casing wall is materially farther from the drum than are other portions of the casing, and gate means for opening and closing the passage-way from the interior of the casing to the space indicated as said channel.

18. In a washing machine of the character described, the combination of a foraminous drum having side and bottom walls mounted for centrifugal rotation on a substantially vertical axis, a casing around the sides and bottom of said drum, the side wall of said casing being substantially close to the side of the drum at one portion thereof and gradually diverging away from the drum spirally, portions of the casing substantially overlapping each other in materially spaced apart relation, an end wall closing the space between said overlapped portions, an inner wall between said overlapped portions, said inner wall being movably mounted whereby the same may be moved into and out of channel forming position, walls forming a channel in communication with the space between said overlapped portions of the casing, said channel opening to the interior of the casing in the lower portion thereof.

19. The combination with the relatively fixed casing of a centrifugal washing machine having a rotatable drum therein, of walls forming a channel adjacent to the body of said casing, one of said walls being mov-

ably mounted to open said channel into the interior of said casing.

20. The combination with the relatively fixed casing of a centrifugal washing machine having a rotatable drum therein, of walls forming a channel adjacent to the body of said casing, one of said walls having an opening from the interior of said channel to the interior of said casing, and door means for closing said opening.

21. The combination with the relatively fixed casing of a centrifugal washing machine having a rotatable drum therein, of walls forming a channel adjacent to the body of said casing, one of said walls being hingedly mounted to form a door to open said channel into the interior of said casing, said casing having an opening to the outer air adjacent to said door, said door being mounted to close said casing opening.

22. The combination with the relatively fixed casing of a centrifugal washing machine having a rotatable drum therein, of walls forming a channel adjacent to the body of said casing, said channel having an opening to the outer air, and a movable door for closing said opening.

ALONZO HUMBERGER.
